DESIGN FOR A COIN PURSE

Denver M. Wright, Brentwood, Mo.

Application August 22, 1940, Serial No. 94,556

Term of patent 3½ years

To all whom it may concern:

Be it known that I, Denver M. Wright, a citizen of the United States, residing in Brentwood, in the county of St. Louis and State of Missouri, have invented a new, original, and ornamental Design for Coin Purses, of which the following is a specification, reference being had to the accompanying drawing, forming part thereof.

Fig. 1 is a front elevational view of a coin purse, showing my new design.

Fig. 2 is a side elevational view thereof.

Fig. 3 is a rear elevational view thereof.

I claim:

The ornamental design for a coin purse, substantially as shown.

DENVER M. WRIGHT.
